UNITED STATES PATENT OFFICE.

REGINALD CHARLES CLINKER, OF INWOODS RUGBY, ENGLAND, ASSIGNOR TO GENERAL ELECTRIC COMPANY, A CORPORATION OF NEW YORK.

ELECTRICAL APPARATUS.

Application filed July 10, 1920. Serial No. 395,295.

To all whom it may concern:

Be it known that I, REGINALD CHARLES CLINKER, a subject of the King of Great Britain, residing at Inwoods Rugby, in the 5 county of Warwickshire, England, have invented certain new and useful Improvements in Electrical Apparatus, of which the following is a specification.

The present invention relates to variable 10 impedances and has for its object to increase the range of adjustment of such instruments and to provide means whereby such adjustment may be quickly and accurately made.

As an example of a type of impedance to 15 which my invention is applicable, there may be mentioned a variable condenser in which a set of movable sectors or vanes enters a set of stationary sectors or vanes. I propose to divide the movable elements of such 20 a condenser into two parts coupled together by a lost motion device or its equivalent so that one of the parts may be adjusted through a certain angle without moving the other part. Means may be provided for 25 clamping the two or more parts together so that they also may be moved as one piece. In practice, one part may be conveniently connected to the operating head or handle and may form the part by which the fine 30 adjustment of the condenser is made, while the other part may be carried upon a spindle coaxial with the operating handle and may constitute the means by which a coarse ad- 35 justment is effected.

I have found that the condenser above 40 described is particularly useful in the wireless art, although by no means limited thereto.

Referring to the drawing, Fig. 1 is a side 45 elevation of a condenser constructed in accordance with my invention, the container being removed and certain parts being shown in a section; Fig. 2 is a top plan; Fig. 3 is a horizontal section taken on the line 3—3 of Fig. 1; Fig. 4 is a vertical section showing a modification of the operating 50 means; and Fig. 5 is a vertical section showing a further modification of the operating means.

The fixed elements of the condenser comprise the fixed sectors *a* supported by pillars *b* set in the insulating base *c* fixed within the top casting *d*.

Plates *e* arranged to cooperate with the 55 stationary plates *a* are mounted upon the

central spindle *f* which is pivoted at its lower end to the frame of the condenser and is secured at its upper end to a boss *k* formed at the center of the scale disc *g*. The plate *l*, likewise designed to cooperate 60 with the fixed plates *a* and to provide by its movement the auxiliary of fine adjustment of the condenser, is carried by sleeve *m* which in turn is fastened to the member *n* provided with two upwardly projecting extensions *o*. The knurled operating head or handle *p* is secured to one of the extensions *o* by a set screw. The movable sector or vane *l* is thus rigidly connected to and rotates with the operating head *p*. In order 65 to provide a lost motion connection between the movable sectors *e* and the operating head *p*, I provide the disc *g* with slots *h* which embrace the extensions *o* and which in the particular construction illustrated are 70 of such a length as to permit the plate *l* to be operated by the head *p* through an angle of 90° before the head commences to move the sectors *e*. The spindle *f* is provided with 75 a friction arm *r* which bears upon a plate *s* secured to the frame of the condenser. This plate which is in circuit with one of the terminals *v* of the condenser serves with the arm *s* to conduct current to the movable plates *e* and *l* and also because of the frictional engagement between plate *s* and arm *r* prevents the sectors *e* from moving before 80 all of the lost motion is taken up. The other terminal *v* of the condenser is connected to the stationary plates *a*. 85

The disc *g* has a scale engraved around its periphery, adapted to coact with a pointer *t* engraved upon the top of the fixed part *d* of the condenser. Handle *p* also has a pointer *u* which coacts with the second scale 90 engraved on the disc *g*. In the construction illustrated in Figs. 1 to 3 this latter scale is so disposed that the pointer *u* points to zero of the scale when the head *p* has been turned in a clockwise direction and has taken up all the lost motion. 100

For the sake of convenience, the main scale on the periphery of the disc *g* when calibrated in terms of capacity represents the capacity of the condenser between the terminals *v* for any position of the main movable sectors *e* and the sectors *l* turned until the pointer *u* points to zero. When using the condenser, as for example in tuning, the head *p* is turned in a clockwise di- 110

rection until the capacity is slightly more than necessary; then turned in a reverse direction with the result that the main sectors *e* remain stationary but sector *l* is slightly withdrawn from the fixed sectors *a*. The total capacity is thus reduced until exact tuning is obtained and the reading of the pointer *u* indicates the amount which must be subtracted from the reading of the pointer *t* to give the true capacity between the terminals of the condenser.

If the total of the capacity needed is somewhat small, so that the main movable element has only to be rotated through less than 90° (the maximum amount of lost motion provided in the example illustrated), then in turning the head *p* back, the sector *l* will be turned so as to leave the fixed sectors *a* entirely. In such a case the capacity change will now be of the opposite sign, that is, vane *l* will begin to add capacity and in order to indicate the amount added a subsidiary fixed scale *w* is provided. This scale is so disposed that when the pointer *u* registers zero there is no capacity between the movable sector *l* and the fixed sectors *a*.

It is sometimes convenient in a condenser of this type to be able to clamp together the movable sectors. Figs. 4 and 5 show two means for accomplishing this. In Fig. 4 the spindle *f* is extended to project through the operating head *p* and is screw threaded at its upper end to receive a clamping nut *x*, which when screwed down upon the brass seating *y* let into the head *p* clamps the spindle *f* to the head and therefore locks together the sectors *e* and *l*. In the form shown in Fig. 5 the pin which secures the head *p* to one of the extensions *o* is movable in a slot *o'*, thus enabling the head *p* to move longitudinally of its axis of rotation. The boss *k* is formed with a clutch face *k'*, which is adapted to cooperate with a clutch face *p'* formed on the under surface of the head *p*. Spring *z* normally holds the head *p* away from the boss *k*, but upon pressing downwardly on the head *p*, the clutch faces engage and the spindle *f* as well as the extensions *o* may be rotated as one piece.

What I claim as new and desire to secure by Letters Patent of the United States, is:—

1. In a condenser, relatively movable elements forming a condenser unit of one capacity range, other relatively movable elements forming a condenser unit of a different capacity range, operating means connected to said former unit to render it responsive to all movements of said operating means and connected to said latter unit through a lost motion device, and means rendering said last mentioned unit responsive to all movements of said operating means.

2. In a condenser, a series of stationary plates, a series of pivoted plates adapted to

be moved into the electrostatic field of said series of stationary plates, a portion of said series of pivoted plates being movable independently of a second portion, means for indicating the angular distance the said first portion has been moved into the said field, a scale movable with said first portion, a stationary scale arranged to cover said first mentioned scale for a part of its path of movement and a pointer movable with said second portion to indicate upon said first mentioned scale the angular position of said second portion relative to said first portion when the movement of said second portion produces a capacity change of one sign and to indicate upon said stationary scale the angular distance said second portion has moved into said field when the continued movement of said second portion in the same direction produces a capacity change of the opposite sign.

3. In a variable impedance, relatively movable elements forming an impedance unit of one range of variation, other variable movable elements forming an impedance of a different range of variation, a single operating means connected to said former unit to render it responsive to all movements of said operating means and connected to said latter unit through a lost motion device, said latter unit being held from movement by said operating means during the lost motion of said device.

4. In a device whose electrical characteristics are adapted to be varied, a series of stationary elements, a series of elements adapted to be moved relative to said stationary elements to vary the electrical characteristics of said device, a portion of said series of movable elements being movable independently of a second portion thereof, means for indicating the distance the first mentioned portion has moved relative to said stationary elements, a scale movable with said first mentioned portion, a stationary scale arranged adjacent said first mentioned scale, a pointer movable with said second portion to indicate upon said first mentioned scale the position of said second portion relative to said first portion when the movement of said second portion produces a change in the electrical characteristics of one sign and to indicate upon the stationary scale the distance said second portion has moved when continued movement in the same direction produces a change in the electrical characteristics of the opposite sign.

5. In a variable condenser, a plurality of stationary elements, a plurality of concentrically mounted rotatable elements in electrostatic relation therewith, one portion of said rotatable elements being movable relative to a second portion thereof, and a single operating member for adjustably

moving said portions relative to said stationary elements and relative to each other.

6. In a variable condenser, a plurality of stationary elements, a plurality of movable elements in electrostatic relation therewith, one portion of said movable elements being movable relative to a second portion thereof, a single operating member for adjustably moving said portions relative to said stationary elements and relative to each other, means for indicating the angular relation between said stationary elements and said one portion of the movable elements,

means for indicating the angular relation between said two portions of the movable elements when said one portion is in certain positions relative to said stationary elements, and means for indicating the angular relation between said one portion and said stationary elements when said one portion is in certain other positions relative to the stationary elements.

In witness whereof, I have hereunto set my hand this 18th day of June, 1920.

REGINALD CHARLES CLINKER.
